Wesley E. Barr
ATTORNEY

UNITED STATES PATENT OFFICE.

HOWARD N. RICHARDS, OF PITTSBURGH, PENNSYLVANIA, ASSIGNOR TO WESTINGHOUSE ELECTRIC & MANUFACTURING COMPANY, A CORPORATION OF PENNSYLVANIA.

CATENARY HANGER.

Application filed October 16, 1922. Serial No. 594,746.

My invention relates to trolley hangers, or the like, of the class having movable clamping jaws, and has particular relation to catenary hangers.

5 In certain devices of the above class, screw means are employed for retaining the clamping jaws in operative position. Such screw means, being separate or removable from the clamping portion of the device, requires 10 manual insertion during the application of the jaw members to the trolley conductor and manual removal in separating the jaw members therefrom. During such operations, the connecting screw means in trolley- 15 hanger devices of the prior art frequently become mislaid or fall out of place, thus causing loss of time and inconvenience in the recovery and replacement thereof.

My invention has for its object, to provide 20 screw means, or the like, that will, at all times, be retained in operative position for use, whether in the application of the hanger device to the trolley conductor or the separation of the device therefrom.

25 In the accompanying drawing,

Figure 1 is a view, in side elevation, of a trolley hanger embodying my invention;

Fig. 2 is a view, partially in end elevation and partially in transverse section, taken 30 along the line II—II, of Fig. 1, and

Fig. 3 is an enlarged transverse sectional view of a portion of the hanger, taken along the line III—III of Fig. 1.

Referring to the drawing, the hanger rod 35 or strap 5 is provided, at its lower end, with a pair of clamping members or jaws 6 and 7, respectively, which are adapted to engage the trolley conductor 8 therebetween. Both the hanger rod and the clamping members 40 thereof may be of any approved form and provided with any suitable means of connection. In the preferred form, however, the jaws are formed of sheet metal.

The respective clamping members 7 and 6 45 are provided with oppositely disposed registerable openings 9 and 10 for the reception of a clamping screw or screws 11. Each opening 9 is countersunk, by means of an annular flange portion 12, to such depth that the conical head of the screw 11 will be approximately flush with the outer surface of the jaw 7. Each opposite opening 10, formed within a cylinder or boss 13, has sufficient length of thread to also avoid pro-

trusion of the screw 11 beyond the outer 55 surface of the jaw 6.

Each of the screws 11 has an annular groove 14 cut or otherwise machined around the shank, at the base of the head, and is further provided with a longitudinally disposed opening 15 by which the screw may be operated from either end by a socket wrench.

Initially, the opening 9, at its inner end, is sufficiently large to permit the passage of the screw shank therethrough, as indicated 65 by dotted lines in Fig. 3.

During assembly, each screw is positioned with its head in the countersunk opening, after which the flange portion 12 is swaged to sufficiently contract it into the groove 14 70 of the screw (as shown in solid lines in Fig. 3) to effect a loose interlocking engagement with the clamp jaw. This interlocking, while entirely preventing loss of the screw 11, is, however, such as will permit free 75 operation thereof.

Each screw being assembled with the clamping jaw 7, as above set forth, it will be readily apparent that the screw may be 80 freely operated in either direction to engage or be disengaged from the opposite clamping jaw 6 without danger of becoming detached or lost.

While I have shown and described a preferred embodiment of my invention, changes 85 in, or substitution of various parts, their arrangement and co-operation may be made within the scope of the invention as set forth in the appended claims.

I claim as my invention:

1. A trolley-conductor device provided 90 with conductor-securing members, one of said members being adapted to carry and retain a one-piece member adapted to connect the other thereto.

2. A trolley-conductor device provided 95 with separable conductor-clamping members and a one-piece connecting means therefor, said means being assembled with, and retained by, one member only and adapted to 100 connect the other thereto.

3. A trolley-conductor device provided 105 with a pair of conductor-clamping members and having a one-piece screw connecting means, said means being carried and retained in operative position by one of said members for connection to the other.

4. A trolley-conductor device provided

with a pair of oppositely disposed conductor-clamping members and a one-piece screw connecting means therefor, said connecting means being carried and retained by, and 5 extending inwardly from, one member and adapted for connection to the other.

5. A trolley-conductor device provided with a pair of conductor-clamping members and a screw connector therefor, said connector being operatively attached at one end to 10 and carried by the one member, the other end thereof being adapted for screw connection to the other member.

6. The combination with one of the clamping members of a trolley-conductor device, 15 of a screw rotatably fixed thereto for connection to another clamping member.

7. The combination with one of a pair of clamping members of a trolley-conductor device, 20 said one member having an opening surrounded by a flange, of a screw adapted for connecting another member thereto and

having a peripheral groove; said screw being operatively carried by engagement of 25 said flange with said groove.

8. A conductor hanger comprising a member having an opening therein to receive a screw head, there being an annular flange about said opening, and a screw having its head disposed in said opening and provided 30 with an annular groove into which said flange projects to form an interlocking connection with the member.

9. A trolley-conductor device comprising 35 a sheet-metal jaw member having an inwardly-turned flange surrounding an opening, and a connecting member provided with a groove engaged by said flange for loosely interlocking the two members.

In testimony whereof, I have hereunto 40 subscribed my name this 9th day of October 1922.

HOWARD N. RICHARDS.
